W. W. JORDAN.
WATCH SETTING LEVER.
APPLICATION FILED JAN. 7, 1918.

1,327,391.

Patented Jan. 6, 1920.

William W. Jordan, Inventor

UNITED STATES PATENT OFFICE.

WILLIAM W. JORDAN, OF DELHI, LOUISIANA.

WATCH-SETTING LEVER.

1,327,391.

Specification of Letters Patent. Patented Jan. 6, 1920.

Application filed January 7, 1918. Serial No. 210,724.

To all whom it may concern:

Be it known that I, WILLIAM W. JORDAN, a citizen of the United States, residing at Delhi, in the parish of Richland and State 5 of Louisiana, have invented certain new and useful Improvements in Watch-Setting Levers, of which the following is a specification.

This invention relates to watches and has 10 for its object to provide an improved setting lever.

Another object of the invention is to provide a lever for stem setting watches which may be operated without removing the 15 watch bezel.

Another object of the invention is to provide a setting lever for watches so formed that when closed in no opening remains in the frame whereby moisture or dust may 20 enter into the works.

With the above and other objects in view I have invented the device illustrated in the accompanying drawings in which—

Figure 1 is a plan view of a watch with 25 certain parts removed to show my invention.

Like reference characters indicate like parts throughout the following specification and in the drawings in which 1 is a watch case and 2 the movement, the face 30 and certain other parts being removed to show the winding and setting mechanism. Mounted upon the plate 3 is a slide or lever 4 having a right angular head 5 operating in a slot 6 projecting through the bezel 35 ring 7. The slide 4 is provided at its inner end with an elongated slot 8 through which the screws 9 and 10 project, whereby said slide is held to its place on plate 3. The heads of said screws may frictionally hold 40 the slide against accidental movement if necessary. Said slide 4 is provided on its edge 11 with a rack 12 which is geared with the segmental gear 13 formed on the arm 14 of the bell-crank lever 15 pivoted upon the 45 screw 16. Rotatably mounted upon the end of arm 17 of said bell-crank lever is a gear wheel 18 so positioned that it is at all times in mesh with the stem operated gear 19, also rotatably mounted on the screw 16. The 50 gear 18 is normally in engagement with the gear 20 which winds the watch spring (not shown).

When the slide 4 is pulled out by means of its head 5, the rack 12 operates rack 13, causing arm 14 of bell-crank lever 15 to be 55 thrown outwardly and its arm 17 to be thrown inwardly, throwing gear wheel 18 into mesh with the transmission gear 21 which is in mesh with the gear 22 of the cannon pinion 23, then the operation of the 60 stem head 24 will set the watch, the rotary movement being transmitted to the cannon pinion instead of to the spring operating gear. By again pushing slide 4 in, the transmission is again changed to the spring 65 operating gear 20.

While the above described setting mechanism is especially adapted for use in connection with my air and moisture proof watch case covered by Patent 1,208,707, yet it can 70 be used to very great advantage with all stem wind and set watches as the straight movement of the setting slide or lever makes a much stronger and more preferable device 75 for all makes of cases, as the open slot in which the arcuate lever operates is done away with and the opening through which the slide operates is kept entirely closed by my form of setting device.

Having now described my invention, that 80 which I claim to be new and desire to procure by Letters Patent is:—

A watch setting device including a bell crank lever having one arm thereof provided at its swinging end with a segmental 85 rack, a pivot pin upon which the bell crank lever is mounted, a shifting gear carried by the other arm of the bell crank lever, a stem operated gear mounted upon the pivot pin and meshing with the shifting gear, a rectilinearly movable slide formed with a rack 90 meshing with the said segmental rack and co-operating therewith to swing the bell crank lever, a spring winding gear arranged to engage the shifting gear at one position 95 of the bell crank lever, and a setting gear arranged to engage the shifting lever at the other position of the bell crank lever.

In testimony whereof I affix my signature in the presence of two witnesses.

WILLIAM W. JORDAN.

Witnesses:

T. C. SPIERS,
C. H. RUNDELL.
